(57) **CLAIM**

The ornamental design for a handheld device, as shown and described.

DESCRIPTION

This application is related to U.S. Design patent application Ser. No. 29/638,857, entitled "Handheld Device," and filed on a date even herewith, the entire contents of which is incorporated by reference herein.

FIG. 1 is a front perspective view of a handheld device showing our new design.

FIG. 2 is back perspective view thereof.

FIG. 3 is another back perspective view thereof.

FIG. 4 is a front view thereof.

FIG. 5 is a back view thereof.

FIG. 6 is a right side view thereof.

FIG. 7 is a left side view thereof.

FIG. 8 is a top view thereof; and,

FIG. 9 is a bottom view thereof.

The broken lines immediately adjacent to the shaded areas represent the bounds of the claim, and the remaining broken lines illustrate portions of the hand held device that form no part of the claimed design; the broken lines and the unshaded surfaces form no part of the claimed design.

1 Claim, 7 Drawing Sheets
